UNITED STATES PATENT OFFICE.

GEORGE T. WILSON, OF BOSTON, ASSIGNOR OF ONE-HALF TO JULIAN D'ESTÉ, OF SALEM, MASSACHUSETTS.

VALVE.

SPECIFICATION forming part of Letters Patent No. 359,948, dated March 22, 1887.

Application filed January 8, 1887. Serial No. 223,767. (No model.)

To all whom it may concern:

Be it known that I, GEORGE T. WILSON, of Boston, in the county of Suffolk and State of Massachusetts, have invented a new and useful Improvement in Valves, of which the following is a specification.

The object of the invention is to provide a valve apparatus to regulate the passage of liquids, (especially water,) so arranged that the liquid may pass through the valve-seat to the outlet-pipe until the back-pressure of the liquid exerts the maximum pressure it is desired that it should exert and tends to rise above it, and that then the liquid shall cease to pass through.

In my invention the valve-seat has a prolongation provided with a port or ports, preferably the latter, around which the valve fits tightly, in order that the liquids shall not act upon the inner area of the valve, and in order that when the valve is raised said ports shall be open to admit the passage of the liquid through the valve-seat to the outlet-pipe, and in order that the valve may be shut by back-pressure of the liquid upon the outer area of the valve and close around said ports and prevent the passage of the liquid through the valve-seat when the back-pressure exerts the maximum pressure it is desired that it should exert and tends to rise above it.

In the drawings, Figure 1 represents in elevation an apparatus embodying my invention, the valve-case C and the cover U to the valve-stem and spring being shown in section. Fig. 2 represents a sectional elevation of the apparatus shown in Fig. 1.

C is the valve-case, which has the inlet A for the admission and the outlet B for the exit of the liquid. The valve-seat T has the prolongation G, which is provided with the ports P. The valve-seat has the gasket H, and the prolongation G of the valve-seat has the cup-washer W and the cup-washer cap F, which latter has the square hole O, to receive a wrench or key to screw the valve seat to the valve-case.

R is the valve-stem, which passes through

the valve-case cap K, and carries the spring S and spring-compressing nut N, and is hollow part way, opening into the valve V, and having an opening, E, above the cap K, to admit of the passage of air from the valve when the valve closes. The cap K is provided with a boss, J, to keep the valve from close contact with the cap K, in order that there may be an outer area, L, of the valve exposed for the liquid to press upon and balance the valve against the lifting force of the spring S, and shut the valve and close the ports P of the valve-seat when the back-pressure upon the area L of the valve exerts the maximum pressure desired and tends to rise above it.

The operation is as follows: The compressing-nut N is turned against the spring S, the spring being compressed thereby and the valve raised. The spring is compressed until the lifting force exerted by it upon the valve is sufficient to keep the valve raised against the back-pressure of the liquid on the outer area, L, of the valve until such pressure has reached the maximum pressure desired and tends to rise above it, when it forces the valve down, air in the valve passing out through the hollow in the valve-stem, and causes the valve to close the ports P and shut off the passage of the liquid through the valve-seat, the valve remaining closed so long as the back-pressure upon the area L of the valve exerts the maximum pressure desired.

I claim—

In a valve apparatus, the combination, with a valve-seat having a prolongation provided with a port or ports, of a valve provided with an outlet for air, said valve being kept raised by a force equal to the maximum back-pressure desired, and being closed by the back-pressure when such pressure exerts the maximum pressure desired and tends to rise above it, substantially as described, for the purpose specified.

GEORGE T. WILSON.
